UNITED STATES PATENT OFFICE.

WALTER PFEIL AND WALTER KOLMEIER, OF FREDERICKSBURG, TEXAS.

WATER HEATER.

Application filed July 29, 1926. Serial No. 125,722.

This invention relates to an improved water heater and it has more specific reference to a device of this kind which is in the form of an attachment for a domestic oil burning stove.

Our principal aim is to supply a device which may be attached to an ordinary oil stove so that persons depending upon stoves of this class may be able to conveniently 10 obtain hot water by simply setting the device removably upon the stove and associating it with the burners, whereby to utilize the flame from the latter to generate heat for heating the water.

15 Briefly, the invention has reference to a device of this kind which includes a water containing tank to set upon the stove top, together with depending tubes for association with the burners, and means for propelling the heat through the tank to effectively heat a considerable portion of the water due to the tortuous passage taken.

The structural features and advantages 25 of the invention will become apparent from the following description and drawings.

In the accompanying drawings forming a part of this application and in which like numerals are employed to designate like parts throughout the same:—

30 Figure 1 is a side view of a conventional oil stove, showing the heater in place thereon,

Fig. 2 is a bottom plan view of the heater per se removed from the stove,

35 Fig. 3 is a central vertical section through the heater,

Fig. 4 is a cross section taken approximately upon the plane of the line 4—4 of Fig. 1,

40 Fig. 5 is an end elevation of the heater,

Fig. 6 is an enlarged transverse section taken approximately upon the plane of the line 6—6 of Fig. 1.

Referring to the drawings in detail, it 45 will be seen that the reference character 1 designates a sheet metal tank of general rectangular form, the same being constructed with a horizontal heat conducting passage 2 spaced slightly above the bottom.

50 This passage opens through the opposite end of the tank. Depending from the bottom wall of the passage are tapered tubes 3 housed within depending sleeves 4 extending downwardly from the bottom of the tank.

55 The space between the tubes and sleeves constitutes a water space and obviously, there

is a web 5 at the bottom connecting each sleeve and tube together. Moreover, as shown in Fig. 4, there is a neck 6 connecting the sleeve with the tube and forming an air 60 passage and this sleeve is covered by a watertight sliding closure 7 in the form of an arcuate plate slidably mounted in vertical guides 8, and carrying a transparent window 9.

Obviously the tubes and sleeves are adapted to rest upon the flange 10 on the oil stove burner 11. Branches 12 of a cold water supply pipe are connected with the sleeves as shown in Fig. 4. Disposed on the exterior of the tank are shields 13, each of which includes a downwardly flared vertical branch 14 and a horizontal branch 15, the last named branch cooperating with the top of the tank. In addition, the hot water supply pipe 16 is connected with the center of the top of the tank as shown. Moreover, there is a depending pipe 18 connected with the branch pipe 12 and with a main water supply pipe 19.

80 A spigot 20 is located in the pipe 18 while a cut-off valve 21 is located in the supply pipe 19. In practice, the usual movable grates or grids are removed from the oil stove and the flat bottom of the tank 1 is placed in contact with the top of the stove as shown in Fig. 1. In so doing, the connected sleeves and tubes are inserted downwardly through the openings in the top of the stove and permit it to rest upon the 85 burner heads as shown plainly in Fig. 4.

Air is supplied to the burners through the adjustable closures and the burners may be ignited through the necks 6. Obviously, when the sleeves and tank are filled with 90 water, and when the burners are lighted, the tubes 3 and walls of the passage 2 will be heated and the surrounding water will in turn be heated. The heat and particles of combustion, which are comparatively few, 95 will pass through the open ends of the passage 2 and upwardly through the shields 13, thus heating greater area of the tank. After the water has been heated to the desired degree, and assuming that it is desired to force it through the hot water conducting pipe 16, the cold water cut-off valve 21 is opened, allowing the cold water to literally flush the tank of the hot water. In some instances, it may be desired to obtain hot water 100 through the spigot 20. However, this is ordinarily used as a drain for the system.

It is believed that by considering the description in connection with the drawings, persons familiar with devices of this class will be able to obtain a clear understanding 5 of the same. Therefore, a more lengthy description is thought unnecessary.

While the preferred embodiment of the invention has been shown and described, it is to be understood that minor changes coming 10 within the field of the invention claimed may be resorted to if desired.

Having thus described our invention, what we claim as new is:—

As a new product of manufacture, a water 15 heater comprising an elongated substantially rectangular tank adapted to rest upon

the top of a stove, said tank being provided with a horizontal passage opening through the opposite end walls, shields associated with the discharge ends of the passage, tubes 20 depending from the passage, sleeves depending from the bottom of the tank surrounding the tubes in spaced relation, connecting webs between the bottoms of the tubes and sleeves, a hot water pipe connected with the top of the tank, and cold water supply pipes 25 connected with the sleeves.

In testimony whereof we affix our signatures.

WALTER PFEIL.
WALTER KOLMEIER.
